UNITED STATES PATENT OFFICE.

OTTOMAR STANGE, OF ASPINWALL, PENNSYLVANIA.

CONCRETE PILING.

1,079,375.

Specification of Letters Patent. Patented Nov. 25, 1913.

Application filed May 27, 1912. Serial No. 700,068.

To all whom it may concern:

Be it known that I, OTTOMAR STANGE, a citizen of the United States, residing at Aspinwall, in the county of Allegheny and State of Pennsylvania, have invented certain new and useful Improvements in Concrete Piling, of which the following is a specification.

This invention relates to a splice for sectional piling made of concrete, or other cementitious material, and it has for its object to provide a rigid and sufficiently strong connection, or coupling for the sections where existing conditions prevent placing 15 piling of the full length required, and driving, jetting and jacking down the same to their ultimate position.

In the accompanying drawing forming a part of this specification—Figure 1 is an elevation of a spliced pile driven to its required depth. Fig. 2 is a vertical section of a pile being driven showing two sections driven and the third section ready to be placed in position for driving. Fig. 3 is a 25 perspective view of the splice.

Referring specifically to the drawing, 1 designates a coupling band or ring of suitable metal which, as shown, is round, but which may be of any other suitable shape 30 to fit the design of the pile for which it is intended. This coupling band is placed on the lower end of each section 8 of piling except the first section, and is secured to the section at the time of casting with its 35 outer surface flush with the outer surface of the section. The end of the section is reduced in diameter to form a shoulder 2 against which the upper end of the band abuts. The other end of the band extends. 40 from the section so that it may be slipped over the upper end of the next section below, the latter also having a shoulder 2^a formed by reducing its diameter at this end, against which shoulder the lower end of the band 45 abuts. A suitable reinforcement 3 is embedded in the sections and may be of various designs and sizes to meet existing conditions. On the lower end of the bottom section is a shoe 4 which is also designed to

50 meet existing conditions. A cushion 5 of cement, mortar or mixture of other cementitious material is placed on the top of the section already driven and remains in place after the act of splicing, the same forming 55 a filler for the joint and preventing voids between the sections. The measurements of

the batters 6 and 7 on the bottom section, from the point to the first splice, depend on the requirements in each case. It is desirable to have the splices conform to a required batter. 60

The splice connecting the various sections allows driving and placing the piling under trestles, buildings and other structures, where there is a lack of sufficient head room 65 to use a pile of the exact length required. By using the splice the various sections can readily be placed and driven, jetted or jacked down to the required depth. Another advantage of the splice is that it enables sections of standard size and lengths 70 to be cast and kept in stock for future use, thus insuring at any time an opportunity for prompt assembling of piling thoroughly seasoned and adaptable to any requirement. 75

The advantage of having a stock of piling which is thoroughly seasoned and ready to use is evident, and it is an important factor in all cases in which concrete or other 80 piling of cementitious material is used.

Should a certain length or lengths of piling be specified, and subsequently be cast and seasoned for a proper length of time, and upon driving it is desired for any reason to place them to a greater depth than 85 originally specified, it is possible with the splice to add such length or lengths as will be necessary to meet the requirements. The splice binds the sections firmly together, making a practically solid piece of the 90 joined parts, and causing them to act as a unit.

The material 5 is placed on top of the section driven, before the section on which the splice is fastened is placed upon it, and 95 said material takes up all unevenness of surface, and acts as a cushion to the pressure or force applied in driving the section, and prevents a crushing of the material where the edges meet. All measurements and 100 sizes are to be governed by the conditions of work, nature of ground, and loads to be superimposed.

I claim:

A pile comprising solid sections of cementitious material, said sections being longitudinally aligned, a cushioning body and filler located between the ends of adjacent sections, and a splicing band carried by one section and projecting from the end thereof, the other section having a circumferentially reduced portion and a shoulder at 110

the inner end thereof, said band projecting beyond the end of that section on which it is mounted for a distance greater than the distance between the end of the other section and its shoulder, whereby the reduced end portion is received within the band and the end thereof engages the shoulder, and space is left between the two sec-

tions in which the aforesaid cushioning body and filler is confined by the band.

In testimony whereof I affix my signature in presence of two witnesses.

OTTOMAR STANGE.
